(57) **CLAIM**

The ornamental design for “bed,” as shown and described.

DESCRIPTION

FIG. 1 is a right elevational view of bed;

FIG. 2 is a bottom plan view of bed;

FIG. 3 is a front elevational view of bed;

FIG. 4 is a top plan view of bed;

FIG. 5 is a left elevational view of bed; and,

FIG. 6 is a back elevational view of bed.

The broken lines are for environmental purposes only and form no part of the claimed design.
